UNITED STATES PATENT OFFICE.

MARSAVAN O'BRIEN, OF LAWRENCE, KANSAS.

GAS-STOVE.

No. 924,183.

Specification of Letters Patent. Patented June 8, 1909.

Application filed February 10, 1908. Serial No. 415,087.

To all whom it may concern:

Be it known that I, MARSAVAN O'BRIEN, a citizen of the United States, residing at Lawrence, in the county of Douglas and State of Kansas, have invented certain new and useful Improvements in Gas-Stoves, of which the following is a specification.

This invention relates to certain new and useful improvements in gas heaters of that type in which is employed a heating drum, and means for causing the products of combustion and heat to take a circuitous path so as to increase the radiation.

The present invention has for its objects among others to provide a simple and cheap construction in which there is a plurality of concentric radiating surfaces, the inner one of which is provided with depending tubes the lower ends of which in turn are received within tubes of greater diameter, the inner cylinder or drum being made removable and having a cap designed to make a close fit over an annular collar or upwardly extending flange on the outer cylinder or drum. The burner is practically closed, sufficient air for combustion being supplied thereto, the products of combustion after circulating around between the drums passing out through a central chamber and exit pipe therefrom. A door is provided to permit access to the burner or for any other purpose that may be required.

Other objects and advantages of the invention will hereinafter appear and the novel features thereof will be particularly pointed out in the appended claim.

The invention is clearly illustrated in the accompanying drawings which, with the numerals of reference marked thereon, form a part of this specification, and in which—

Figure 1 is a substantially central vertical section through a heater embodying my invention, with the gas supply pipe in elevation and with a portion broken away. Fig. 2 is a cross section on the line 2—2 of Fig. 1 looking in the direction of the arrow.

Like numerals of reference indicate like parts in the different views.

Referring to the drawings 1 designates an outer cylinder or drum designed to be mounted upon suitable supports as the legs 2, the bottom of said drum being closed except as hereinafter specified. At its upper end there is an annular opening 3 surrounded by the collar or flange 4 extending upwardly above the top 5 of the cylinder or

drum. In the bottom 6 of this cylinder or drum are the openings 7, of any desired number, in this instance shown as three, and from this bottom 6 there extend upwardly the short tubes 8, joined to the bottom 6 and at their upper ends joined to the bottom 9 of the cylinder or drum 10 which is concentric with the cylinder 1. This cylinder or drum 10 is of less height than the cylinder 1, as seen in Fig. 1, being open at the top, as seen at 11.

12 is the inner cylinder. It is open at the top, as seen at 13, its bottom 14 being provided with a plurality of openings 15, 70 in this instance three, corresponding with the number of openings 7 in the bottom 6 of the cylinder 1, and secured in these openings are the tubes 16 which depend therefrom and extend within the tubes 8, as seen clearly in Fig. 1. Extending outwardly from the top of this inner cylinder or drum is a flange 17 from which depends the annular collar or flange 18 which is designed to snugly embrace the upwardly extending 80 flange or collar 4 of the cylinder 1 to make a tight joint therewith, as seen clearly in Fig. 1.

19 is a closure, which may be of any suitable form, permitting access through the 85 opening 20 to the space between the cylinders 10 and 12 to allow of reaching the burner to light it, or for repairs or other purposes.

Extending upwardly through the bottoms 90 6 and 9 of the cylinders 1 and 10 is a pipe 21 carrying at its upper end a burner 22 of any suitable or well known type, the said pipe 21 being connected with the pipe 23 leading from a suitable source of fuel supply such as gas.

The inner cylinder or drum 12 with its tubes 16 can be removed at any time for repairs or other purposes, being lifted out by its flange 18, as will be readily understood.

In use, the gas being turned on and ignited at the burner, the course of the heat and the products of combustion will be as indicated by the arrows in Fig. 1 being from the space between the cylinders 10 and 12 upward and out of the open end of the cylinder 10, thence downward in the annular space between the cylinders 1 and 10 and thence toward the center of the device and out through the exit 24. By this means 105 the heat and products of combustion are brought into direct contact with all of the

cylinders and tubes and the air which is drawn in through the tubes 8 and 16 is readily heated and the heat is brought into direct contact with the various cylinders which greatly increases the radiation.

What is claimed as new is:—

The combination in a heater, of an outer cylinder constructed with top and bottom closing end portions and with openings in its bottom end, an adjacent inner cylinder provided with an open upper end and a closed lower end, pipes arranged depending from the bottom of said adjacent inner cylinder, said pipes being arranged providing open passageway through the bottom of the outer cylinder and leading into said adjacent cylinder, an innermost cylinder located in said adjacent cylinder, the innermost cylinder being constructed with an open top end and a closed bottom end, and also made shorter than said adjacent cylinder, pipes with open ends arranged de-

pending from the innermost cylinder, said pipes being constructed extending into the pipes depending from the bottom of said adjacent cylinder, providing passageways leading from aforesaid holes in the bottom of the outer cylinder to and into, the innermost cylinder, a burner arranged in said adjacent cylinder, said burner being located under the bottom of the innermost cylinder, means adapted to convey gas to the burner, the outermost cylinder being provided with an exit opening, said outer, adjacent, and innermost cylinders being constructed and arranged providing up and down passageways therebetween, leading from said burner to aforesaid exit opening.

In testimony whereof I affix my signature in presence of two witnesses.

MARSAVAN O'BRIEN.
